UNITED STATES PATENT OFFICE.

JAMES WILLIAM BAGBY, OF WICHITA, KANSAS.

PUMP.

No. 888,574.

Specification of Letters Patent.

Patented May 26, 1908.

Application filed August 9, 1906. Serial No. 329,924.

To all whom it may concern:

Be it known that I, JAMES WILLIAM BAGBY, a citizen of the United States, residing at Wichita, in the county of Sedgwick and State of Kansas, have invented a new and useful Pump, of which the following is a specification.

This invention relates to a lift pump and has for its general object to improve and simplify the construction and operation of pumps of this character so as to render them more efficient in operation.

Furthermore, the object of the present invention is to provide a pump embodying a pair of coöperatively arranged pistons having a novel arrangement and construction of valves, the construction and mountings for the valves simplifying and cheapening the cost of the pumps, while their relative arrangement insures the passage of water therethrough without undue loss in friction.

Another object of the invention is to provide a double piston pump so arranged that the water will pass successively through the pistons in substantially the same spiral direction, the pistons being arranged to reciprocate alternately so as to produce a double acting pump.

With these objects in view, and others, as will appear as the nature of the invention is better understood, the invention comprises the various novel features of construction and arrangement of parts, which will be more fully described hereinafter, and set forth with particularity in the claims appended hereto.

In the accompanying drawing, which illustrates one of the embodiments of the invention, Figure 1 is a central vertical section of a double-acting pump, the lower end and intermediate portion of the casing being broken away. Fig. 2 is a perspective view of one of the pistons showing several of the valves removed, and the remaining valves closed. Fig. 3 is a side elevation of a piston showing the valves open. Fig. 4 is a diagrammatic view of one of the ports of a piston with the valve thereof open to show the passage of the water therethrough.

Corresponding parts in the several figures are indicated throughout by similar characters of reference.

In the present instance, I have elected to illustrate the invention as a double acting pump, but it is to be understood, however, that certain features of the invention are

capable of being carried out in connection with a pump of the single acting type.

Referring to the drawing, 1 designates the pump casing which may be of any desired length or diameter and at the upper end thereof is provided a discharge spout 2. Arranged for reciprocation in the casing 1 are upper and lower pistons 3 and 4, respectively. The lower piston 4 is provided with a central opening for the reception of the lower end of the plunger rod 5. This rod extends through central openings 6 and 7, respectively, in the top piston and top 8 of the casing. The upper piston 3 is provided with two rods 9 rigidly connected at their lower ends thereto at points on opposing sides of the opening 6. The upper ends of the several piston rods are each united to an independent connecting rod or pitman 10, which pitmen are connected with a two-throw crank 11. The crank 11 is constructed with a central arm 12 to which the pitman on the middle piston rod is connected, and two correspondingly extending arms 13 to which the pitmen of the piston rods 9 are connected. By this arrangement, one piston is reciprocated in one direction, while the other piston is simultaneously reciprocated in the opposite direction, so that the pump will deliver a constant flow of water, as the crank shaft is rotated. The crank shaft is mounted on the upper end of standards 14 and is rotated by means of a crank handle 15 secured to one end thereof. It is obvious that the arrangement of the piston rods may be reversed should it be found desirable.

The pistons are each preferably made of sheet metal of suitable thickness and of such material as to withstand the chemical effect of the liquid the pump is designed to operate with. The piston comprises a dish-shaped body 16 having its edge turned down into a cylindrical flange 17 so as to add stiffness to the piston. The body is provided with a plurality of sector-shaped ports 18 punched out of the same, leaving spokes 19 connecting the rim 20 with the central portion 21. The punching of the ports is so performed as to leave ribs 21' along one edge of the spokes, which ribs are turned downwardly at an angle to the plane of the piston the ribs of the upper piston extending at an incline to the plane thereof, while those of the lower piston extend either parallel to the axis of the piston, or they may, in order to simplify the construction, be made similar to those of

the upper piston, as this enables both pistons to be punched and formed as duplicates. Over each port 18 is mounted a sector-shaped valve 22 arranged to open upwardly. These valves are each hinged along one of its radial edges so that it will open to an inclined position more or less approximating the incline of the vanes 21', so that the passage formed between each valve and the adjacent rib or 5 vane 21 will slightly contract in an upward direction and be disposed with its axis inclined to the horizontal. By this arrangement, the water will pass through the pistons, as they move downwardly, in separate 10 streams, which, by reason of the inclination of the discharging passages at the ports and of the curvature of the pump casing, will partake of a spiral direction. The valves may be hinged to the body of the piston in 15 any desired manner. By preference, I prefer the simple construction shown, comprising a looped wire 23 passing through the registering openings 24 of each valve and spoke. These loops are so proportioned as to permit 20 the valves to swing upwardly to the inclined or partially opened position shown in Figs. 25 3 and 4.

In a pump provided with pistons of the character described, the downward movement of the lower piston causes the water to 30 pass through the several ports beneath the inclined valves in a screw-like course, the valves opening normally to positions similar to those shown in Fig. 3. As the piston 4 moves downwardly, water is transferred from the lower side thereof through the several ports to the space above the piston and, in so doing, acquires a rotary movement, so that by the time the piston reaches the lower 35 limit of its stroke, the body of water above the same is in more or less motion, so that as the lower piston 4 moves upwardly and the upper piston 3 moves downwardly, the rotary movement of the water during the relative 40 proximating movements of the pistons causes a relative spiral movement between the water and the upper piston, the pitch of the spiral corresponding substantially to the angle of inclination of the valves and ribs of 45 the upper piston. Thus the resistance of the water passing through the upper piston due to the combined action of the said piston moving downwardly, and the lower piston moving the water upwardly will be substantially 50 reduced.

The diagram shown in Fig. 4 illustrates the manner in which each valve and adjacent vane 21' causes the water passing through the port to acquire an upwardly inclined direction. The water thus discharged through the port strikes upon the wall of the casing 1 and is deflected and given a spiral movement.

This invention is of particular utility when 60 applied to pumps having reciprocatory pis-

tons provided with valves pivoted to swing on radial axes; as the inclination of the valves due to the partial opening produces a relative rotary or spiral movement of the water in passing therethrough, and by employing a pair of coöperating pistons both employing valves turning on radial axes, the rotary motion of the water will serve to direct it through the upper piston in a direction parallel to the planes of the valves of the upper piston when 65 open, and the inclination of the ribs serves to present the metal edgewise to the flowing water to reduce resistance, and also to stiffen the spokes on which the valves are pivoted. In the particular embodiment shown, the 70 ribs of both pistons are inclined, as this enables the pistons to be punched and formed as duplicates, and the friction on the water would probably be slightly reduced were the ribs on the lower piston turned more nearly 75 at right angles to the plane of the piston; but the inclination of the valves of the lower piston induces rotary movement of the water, and by associating with the lower piston, an upper piston constructed as described, a 80 greater efficiency is obtained in a pump of 85 this type. Moreover, the continuous flow of the water after passing through the upper piston provides a source of water supply that is particularly adapted to hydraulic mining 90 and analogous uses wherein the uniform flow of the water increases the efficiency of the water as a dislodging and washing medium.

A pump constructed in accordance with the present invention may be manufactured 95 and sold at a low cost, and it is relatively light in weight, as its parts may be manufactured almost wholly by means of dies, the pistons being each composed of a single piece of sheet metal wherein the valve openings are 100 formed by punching out segmental sections, the radial spokes formed between the valve openings providing supports for the valve pivots, and these supports and the peripheral rim of the piston are stiffened or reinforced by the angularly arranged ribs which 105 are arranged edgewise to the flat sides of the spokes, and as the water in passing through the partly opened valves of the lower piston 110 will be given a spiral movement, the inclined ribs of the upper piston will offer a minimum 115 resistance to the water in passing therethrough, as these ribs are presented edgewise to the water.

What is claimed is:—

1. In a pump the combination with a casing; of a piston adapted to operate therein and composed of a stamping of sheet material having a circumferential flange adapted to coöperate with the inner walls of the 12 casing and provided with a series of sector shaped ports, radially extending spokes being formed between the ports, and the material at one side of each port being deflected angularly to the plane of the piston, and 13

separate flat valves connected to the piston, and disposed to cover the respective ports, said valves being disposed to swing open on substantially radial axes.

- 5 2. In a pump, the combination with a casing, of a piston adapted to operate therein and composed of a stamping of sheet material having a circumferential flange adapted to coöperate with the inner walls of the 10 casing and provided with a series of sector-shaped ports, radially extending spokes being formed between the ports, and the material at one side of each port being deflected angularly to the plane of the piston, flat 15 sector-shaped valves adapted to cover the respective ports, and a looped member passing through perforations in one edge of each valve and in the respective spokes of the piston for pivotally mounting the valves on substantially radial axes.
3. In a pump the combination with a casing; of a piston adapted to operate therein and composed of a stamping of sheet ma-

terial having a circumferential flange adapted to coöperate with the inner walls of the 25 casing and provided with a series of sector-shaped ports, radially extending spokes being formed between the ports, and the material at one side of each port being deflected angularly to the plane of the piston, and 30 separate flat valves connected to the piston and disposed to cover the respective ports, said valves being disposed to swing open on substantially radial axes, a valved piston below the first mentioned piston and within 35 the casing, an operating shaft having diametrically opposed cranks, and operative reconnections between the cranks and the respective pistons.

In testimony that I claim the foregoing as 40 my own, I have hereto affixed my signature in the presence of two witnesses.

JAMES WILLIAM BAGBY.
